UNITED STATES PATENT OFFICE.

JOHN C. GREENO, OF KANSAS CITY, MISSOURI.

CANE.

1,050,124.

Specification of Letters Patent. Patented Jan. 14, 1913.

Application filed April 29, 1912. Serial No. 693,800.

To all whom it may concern:

Be it known that I, JOHN C. GREENO, a citizen of the United States, and a resident of Kansas City, in the county of Jackson 5 and State of Missouri, have invented certain new and useful Improvements in Canes, of which the following is a specification.

My invention relates to improvements in canes.

10 The object of my invention is to provide a tubular cane with which material, such as sand, may be carried and dispensed as needed upon icy pavements for insuring a sure footing for the person carrying the 15 cane.

The novel features of my invention are hereinafter fully described and claimed.

20 In the accompanying drawings which illustrate the preferred form of my invention, Figure 1 is a side elevation of my improved cane. Fig. 2 is a central vertical section of the same.

Similar reference characters designate similar parts in the different views.

25 The cane is provided with a tubular body 1 the upper end of which is externally screw threaded and has fitted thereto a laterally extending handle 2 adapted to coöperate with a finger hold 3, which extends through

30 an aperture which may be a longitudinal slot 4 in the body and which is secured to and forms part of a receptacle 5, which is longitudinally movable in the body 1 and has its closed lower end provided with a

35 central discharge opening adapted to receive therein and be closed by a central vertical conical extension 6 provided on the upper end of a plug 7 mounted, preferably removably by a screw threaded connection, in

40 the lower end of the body 1. The body 1 below the receptacle 5, and preferably at the lower end of the extension 6 is provided with one or more lateral discharge openings 8 through which the sand from the

45 receptacle 5 may be discharged upon the pavement when the receptacle 5 is upwardly drawn by grasping the handle 2 and finger hold 3. Said openings 8 and the interior of the body 1 below the receptacle 5 serve to

50 form a passage for the conduct of the sand or other material from the receptacle 5.

The receptacle 5 is provided at its upper end with a removable cover comprising a flat circular plate 9 against which bears the 55 lower end of a coil spring 10 the upper end of which bears against the handle 2. The

spring 10 normally serves to force the receptacle 5 downwardly to a position in which the discharge opening of said receptacle will be closed by the extension 6, which thus 60 becomes a valve.

In operating the invention, the handle 2 is first removed, after which the spring 10 and cover 9 are removed, upon which sand may be placed in the receptacle through the upper end thereof. The cover 9, spring 10 and handle 2 are then replaced. When a person desires to discharge sand to secure a sure footing, he grasps the finger hold 3 with the hand which grasps the handle 2 70 and draws said finger hold and the receptacle 5 upwardly, thus opening the outlet of the receptacle by withdrawing said receptacle from the conical extension 6. The sand will then pass from the receptacle 5 into the 75 body in the space below the receptacle, and being diverted outwardly by the conical extension 6 will escape through the openings 8. As soon as sufficient sand has been discharged to effect the purpose, the finger 80 hold 3 is released, upon which the spring 10 will force the receptacle 5 downwardly to the closed position shown in Fig. 2.

I do not limit my invention to the structure shown and described, as modifications, 85 within the scope of the appended claims, may be made without departing from the spirit of my invention.

Having thus described my invention, what I claim and desire to secure by Letters Patent, is:—

1. A cane having a tubular body provided with an aperture, a discharge opening and a valve, a receptacle for sand longitudinally movable in the body and having a discharge 95 opening adapted to be closed by said valve, the receptacle having a finger hold extending through the aperture for moving the receptacle to the open position, and means for normally forcing the receptacle to the 100 closed position.

2. A cane having a tubular body provided with an aperture, a discharge opening, and a plug having a central conical extension extending above said opening and serving 105 as a valve, a receptacle for sand longitudinally movable in the body above said opening and having a discharge opening adapted to be closed by said conical extension and having a finger hold extending laterally 110 through said aperture, and a spring for normally forcing said receptacle to a posi-

tion in which said valve will close said opening in the receptacle.

3. A cane having a tubular body provided with an aperture, a discharge opening, a plug in the lower end of the body having a conical central extension, and a handle secured to the upper end of the body, a receptacle for sand longitudinally movable in the body and having a laterally extending finger hold extending through said aperture adjacent to the handle and having in its lower end a discharge opening disposed above the discharge opening in the body and adapted to be closed by said conical extension, and a spring for moving the receptacle to the closed position.

4. A cane having a tubular body provided with a threaded upper end having a longitudinal slot, a handle fitted to the threaded

portion, a discharge opening adjacent to the lower end, and a plug in the lower end having a central conical extension, a receptacle for sand longitudinally movable in the body above said opening and having a discharge opening in its lower end adapted to be closed by said extension, and having a laterally extending finger hold extending through said slot, and a spring in said body and bearing against the receptacle and handle for normally forcing the receptacle to the closed position.

In testimony whereof I have signed my name to this specification in the presence of two subscribing witnesses.

JOHN C. GREENO.
